UNITED STATES PATENT OFFICE

2,480,606

POWDER DISPENSING DEVICE

John Rabbitt, New York, N. Y.

Application January 30, 1945, Serial No. 575,282

4 Claims. (Cl. 222—189)

1

This invention relates to a dispensing device, and more particularly to such a device adapted for the dispensing of pulverized or granular substances, such as salt, sugar, medicinal powders, or other similar substances.

A primary object of this invention is the provision of such a dispensing device provided with auxiliary apertures therein, whereby the powder contained in the device may be dispensed readily in the event that the normal pouring apertures or openings are clogged by moisture or dampness.

A further object of the invention is the provision of such a device having closure means for said auxiliary openings in order to protect the same when their use is not necessary.

Still another object of the invention is the provision of such a device which will be sturdy and durable in construction, reliable and efficient in operation, and relatively simple and inexpensive to manufacture and assemble.

Further objects reside in the combinations of elements, arrangements of parts, features of construction, all as will be more fully pointed out hereinafter and disclosed in the accompanying drawings, wherein there is shown a preferred embodiment of this inventive concept.

In the drawings:

Figure 1 is a side elevation view of one form of device embodying this inventive concept, the auxiliary openings being shown exposed.

Figure 2 is a longitudinal section taken through the center of the device shown in Figure 1, or substantially along the line 2—2 of Figure 5, as viewed in the direction indicated by the arrows.

Figure 3 is a sectional view taken substantially along the line 3—3 of Figure 1, as viewed in the direction indicated by the arrows.

Figure 4 is a plan view of a constructional detail, and

Figure 5 is a top plan view of the device.

Similar reference characters refer to similar parts throughout the several views of the drawings.

Having reference now to the drawings, the device of the instant invention is comprised of a receptacle generally indicated at 10, and of cylindrical configuration, provided with an inwardly offset threaded flange member 11 forming a shoulder 12, on which shoulder is adapted to rest the lower edge 13 of a top or cover member 14, the interior of the lower portion of the member 14 being threaded to coact with the threads on the flange 11, to provide a completed container wherein the top and bottom sections are substantially flush.

2

The cover member 14 is provided at its upper extremity with a plurality of perforations 15, adapted to serve as the normal pouring or dispensing opening for the device. An interior partition 16 similarly provided with a plurality of openings or apertures 17 is positioned in the top 14 below the upper extremity thereof.

Extending through the side wall of the top 14 at a point below the partition 16 are a plurality of secondary pouring openings or apertures 18. The cover 14 is provided with a plurality of annular grooves 19 positioned adjacent and below the secondary pouring openings 18. Seated in the grooves 19 is a circular closure member 20, provided on its interior face with ridges 21 adapted to coact with the grooves 19.

From the foregoing, the method of operation of the device should now be readily understandable. The band 20 is normally rotated in such manner as to cover the openings 18, and the device utilized in the manner of a conventional salt shaker or the like, the substance contained therein being dispensed through the openings 17 and 15. When, however, the openings in the top 25 of the device become clogged, the band 20 may be rotated until the secondary pouring openings 18 are exposed, and the salt or other substance contained therein readily poured out through these secondary openings. The plate 16 and the 30 cover member 20 serve normally to preclude the clogging of these secondary openings such as might be occasioned by moisture or dampness or the like.

Obviously, the device may be filled by separating the threaded members 10 and 14.

From the foregoing it will now be seen that there is herein provided a device accomplishing all the objects of this invention and others including many advantages of great practical utility and commercial importance.

As many embodiments may be made of this inventive concept, and as many modifications may be made of the embodiment hereinbefore shown and described, it is to be understood that all matter herein is to be interpreted merely as illustrative and not in a limiting sense.

I claim:

1. A dispensing device for solid, comminuted material including a container having an open end, a closure cap for said open end, primary dispensing means in the end of said closure, secondary dispensing means in the side of said closure, a shielding means rotatably embracing said closure and said secondary dispensing means, said shielding means and said closure having a

cooperating annular rib and groove fastening means, said shield consisting of an arcuate strip having the adjacent ends spaced to provide a dispensing opening.

2. The combination of claim 1 wherein said fastening means comprises a laterally extending rib on the inner surface of said shielding means and an annular groove on the side wall of said container.

3. The combination of claim 2 including a perforated partition in said closure cap disposed intermediate the ends thereof and between said primary and secondary dispensing means.

4. The combination of claim 3 wherein said container is provided with a reduced, externally threaded upper neck portion, said closure being an internally threaded sleeve engaging said neck, the outer surface of said closure and said container forming a continuous cylindrical surface.

JOHN RABBITT. 20
